UNITED STATES PATENT OFFICE.

EDWARD S. MORRIS, OF LOS ANGELES, CALIFORNIA.

DESIGN FOR A FURNITURE LEG OR SIMILAR ARTICLE.

Application filed October 6, 1924. Serial No. 10,972. Term of patent 7 years.

To all whom it may concern:

Be it known that I, EDWARD S. MORRIS, a citizen of the United States, residing at Los Angeles, in the county of Los Angeles and State of California, have invented a new, original, and ornamental Design for Furniture Leg or Similar Article, of which the following is a specification, reference being had to the accompanying drawing, forming a part thereof.

In the drawing, Fig. 1 is an elevation of the leg and column indicating in dotted lines the typical use of such leg and column for supporting and forming a frame member of an article of furniture. Fig. 2 is an enlarged cross section of line 2—2 of Fig. 1, and Fig. 3 is an enlarged bottom plan.

I claim:

The ornamental design for a furniture leg or similar article, as illustrated.

EDWARD S. MORRIS.
